UNITED STATES PATENT OFFICE

2,167,524

WINDOW-CLEANING DEVICE

Andrew Renik, New York, N. Y.

Application August 25, 1937, Serial No. 160,794

2 Claims. (Cl. 306—28)

This invention relates to window cleaning devices.

An object of this invention is to provide a window cleaning device for cleaning the outside of windows, while standing inside the room, to eliminate danger of falling.

Yet another object of this invention is to provide in a window cleaning device of the character described, highly improved means for interchanging the brush and squeegee.

Still another object of this invention is to provide a rugged and durable window cleaning device of the character described, which shall be easy to manipulate, simple to assemble, relatively inexpensive to manufacture, and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention,

Fig. 1 is a side, elevational, cross-sectional view of a window, and cleaning device embodying the invention;

Fig. 2 is a longitudinal, cross-sectional view of a portion of the handle, illustrating the joint between the parts of the handle;

Fig. 3 is a perspective view of one end of the handle with the brush removed;

Fig. 4 is a perspective group view illustrating the brush, and modified means to attach the same to the handle;

Fig. 5 is a top plan view of a squeegee adapted to be used with my improved handle; and

Fig. 6 is a longitudinal, cross-sectional view similar to Fig. 2, but illustrating the joint with a wedge block to change the angle of the handle.

Referring now in detail to the drawing, 10 45 designates a window frame provided with double hung window sashes 11 and 12, slidably mounted in the frame. In Fig. 1, numeral 14 designates a window cleaning device embodying the invention for cleaning the outside of the window sashes 11 and 12. The device 14 comprises a handle 15 which may be made of parts or sections 16 and 17, and a brush 18 at one end of the handle.

The handle part 16 may be made of wood or 55 any other suitable material, and is curved sub-

stantially throughout its length. At one end thereof, the handle portion 16 has a conical straight end portion 20, and extending from said portion, is a curved portion 21 of relatively small radius, from which there extends a portion 22 of relatively large radius. The other end of the handle part 16 is of slight curvature, as shown at 23.

At the outer end of the portion 23, the handle part 16 has a tapered or inclined surface 24, for 10 the purpose hereinafter appearing. The tapered end of the handle is formed with a transverse through opening 25, for the purpose hereinafter appearing.

Attached to the handle part 16, adjacent the portion 20 thereof, is an eyelet 28. Pivoted to said eyelet is an attachment member 29, made of a single piece of resilient wire having an intermediate looped portion 30, engaging said eyelet. Extending from the looped portion 30, are a 20 pair of oppositely hooked portions 31 and 32 disposed substantially in the same plane. As shown in Fig. 3 of the drawing, the hook portion 32 is longer than the hook portion 31. The portion 20 of the handle part 16, is formed with a small 25 opening 33 adapted to receive the hooked end of the hook portion 31.

The handle part 17 may be slightly curved and has a tapered surface 35 at its outer end complementary to the tapered surface 24. When 30 the surfaces 24 and 35 are in mutual contact, the handle part 17 forms an extension of the handle part 16. The tapered end of the handle part 17 has a through opening 36 adapted to register with the through opening 25.

It will be noted that one end of the handle part 17 is tapered at 17a, so as to permit a cleaning implement to be secured thereon.

Attached to the top surface of the part 17, adjacent the tapered end thereof, is a plate 37 40 screwed thereto as by screw 38. The plate 37 has an upstanding lip 39 adjacent the outer end thereof. Said plate 37 has an opening 40 registering with the opening 36. A bolt 41 extends through the registering openings 25, 36 and 40, 45 and serves to attach together the handle parts 16 and 17. A wing nut 42 on the bolt 41 serves to tighten the bolt.

A metal strap 44 screwed to the tapered end of the handle part 16, as by screw 45, surrounds 50 the mutually contacting tapered portions of the handle parts 16 and 17 to firmly hold said handle parts against separation.

The brush 18 may be of any usual construction and has a back 50 provided with a pair of in- 55

clined sockets 51. Attached to the back 50 is an apertured metal plate 52 having an aperture or opening 53. The plate 52 is disposed in a plane perpendicular to, and extending longitudinally of the back 50.

5 The method of attaching the brush to the handle will now be described. The outer end of the handle part 16 is shown in dotted lines in Fig. 4 in attached position with respect to the brush 50. The tip of the tapered portion 20, of the handle part 16, fits within one of the sockets 51. The end of the hook portion 31 engages within the opening 33, and the hooked end of the hook 32 engages within the opening 53 of the plate 52. 10 The member 29 being made of spring wire is maintained under tension when the hook portion 32 engages the plate 52 for holding the brush on the handle.

If desired the brush 18 may be connected to the 20 handle part 16 for pivotal movement with respect thereto. To this end there is provided a conical tubular metallic member 60 provided with a pair of spaced, flat, apertured ears 61 at the smaller end thereof. The plate portion 52 of the brush, 25 may be inserted between the apertured ears 61, and a bolt 62 passed through the apertures in said ears and through the opening 53, the bolt being tightened by wing nuts 63. The brush 18 may then pivot about the axis of the bolt 62. The 30 tapered portion 20, of the handle part 16, is inserted into the conical tubular member 60 and attached thereto by a screw passing through an opening 64 in said member, or in any other suitable manner.

35 It will now be understood that a person standing within the room and holding the handle 15 may brush the outside of the windows for cleaning the same. When the member 60 is used, the brush 58 may pivot about the axis of the bolt 62 during the brushing or cleaning operation.

40 The brush 18 may be replaced by a squeegee 65. The squeegee comprises the wiping blade 66 held by an elongated, channel shaped member 67. Extending from the channel shaped member 67, at right angles thereto, is a conical tubular member 45 68 to receive the tapered portion 20 of the handle. Fixed to the middle of the channel shaped member 67, is an inclined plate 69 formed with an opening 70. The tubular portion 68 is formed with an opening 71 aligned with the opening 70, and registering with opening 33 in tapered portion 20 of the handle. To attach the squeegee 65 to the handle, the hook portion 31 is engaged within the openings 71 and 33, and the hook portion 32 is engaged within the opening 70.

55 Means is provided for changing the angle of the handle 15. To this end, there may be inter-

posed between the tapered surfaces 24 and 35, a wedge shaped block 80, having a central elongated notch 81 to straddle the bolt 41. To interpose the block 80, the wing nut 42 is first loosened sufficiently to permit insertion of the wedge. It will be noted that the strap 44 engages the lip 39 of the plate 37 when the wedge block is inserted between the handle part 16 and 17.

The handle part 16 and 17 may be made of laminated sheets of wood or of any other material.

10 It will thus be seen that there is provided a device in which the several objects of this invention are achieved, and which is well adapted to meet the conditions of practical use.

15 It is further to be understood that in some cases it may be desired to eliminate the two part handle so as to construct it out of a single member. In this instance the handle part 16 and 17 will be integrally formed, but of course will be constructed of the curved shape as shown in Fig. 1.

20 As various possible embodiments might be made of the above invention, and as various changes might be made in the embodiments above set forth, it is to be understood that all matter herein set forth or shown in the accompanying drawing is to be interpreted as illustrative and not in a limiting sense.

25 Having thus described my invention, I claim as new and desire to secure by Letters Patent:

30 1. In combination, a handle having a conical portion at one end, an eyelet attached to said handle adjacent said conical portion, said conical portion being formed with an opening adjacent said eyelet, a brush having a socket receiving the outer tip of said conical portion, and a member 35 made of a single piece of wire, having an intermediate looped portion receiving said eyelet, and a pair of hook portions extending from said loop portion, one of said hook portions engaging the opening in said conical portion, an apertured member fixed to said brush, and said other hook portion engaging the aperture in said last mentioned member.

40 2. In combination, a handle having an opening adjacent one end thereof, an eyelet on said handle adjacent said opening, a member made of single piece of resilient wire having an intermediate portion engaging said eyelet, and a pair of oppositely hooked portions disposed in the same plane, a cleaning implement having a socket receiving the tip end of the handle, an apertured member on said implement, one of said hooked portions engaging said opening in said handle and the other hook portion engaging the aperture in said 45 apertured member.

50 55 ANDREW RENIK.
